BY

UNITED STATES PATENT OFFICE.

JOHN T. NELSON, OF SIOUX FALLS, SOUTH DAKOTA.

CORNER-SUPPORT FOR PICTURE-FRAMES.

SPECIFICATION forming part of Letters Patent No. 700,548, dated May 20, 1902.

Application filed January 11, 1902. Serial No. 89,335. (No model.)

To all whom it may concern:

Be it known that I, JOHN T. NELSON, a citizen of the United States, residing at Sioux Falls, in the county of Minnehaha and State 5 of South Dakota, have invented new and useful Improvements in Corner-Supports for Picture-Frames, of which the following is a specification.

This invention relates to a corner-support for picture-frames and the like; and the object of the same is to provide a simple and effective adjustable corner attachment for a picture-frame which is adapted to hold the glass in close relation to a picture and having means for receiving a surrounding flexible support, to which a hanger element is secured, to thereby distribute the supporting strain equally at different points on the combined glass and picture.

15 The invention consists in the construction and arrangement of the several parts which will be more fully hereinafter described and claimed.

In the drawings, Figure 1 is a front elevation of a combined glass and picture, showing the improved corner-support applied thereto. Fig. 2 is a rear elevation of the same. Fig. 3 is a detail perspective view of one of the corner-supports. Fig. 4 is a blank from 30 which the corner-support is shaped. Fig. 5 is a section on the line 5-5, Fig. 1.

Similar numerals of reference are employed to indicate corresponding parts in the several views.

35 The numeral 1 designates a glass or other transparent face-plate, against the rear face of which a picture 2 is adapted to be held by the improved corner-supports. Each of the corner-supports is formed from a blank 3, 40 (clearly shown by Fig. 4,) having any suitable ornamental configuration or design and approximately triangular in contour. From the outer edges of the body of the blank bendable tongues 4 project, two of the said 45 tongues being in the present instance constructed on each edge, though it will be understood that this number may be increased without departing from the principle of the invention. From the apex of the body of the 50 blank an elongated bendable arm 5 projects. The tongues 4 are doubled or bent over the body of the blank to provide hooks 6, as

clearly shown by Fig. 3, and the arm 5 is rolled to form an adjustable eye or loop 7. In assembling the parts of the picture and 55 the corner-supports the photograph or other picture 2 is placed against the glass 1 and the corner-supports are applied, as shown by Fig. 1, with the hooks 6 engaging the back of the corner portions of the picture, as clearly 60 shown by Fig. 2. Owing to the bendable nature of the hooks 6 any thickness of glass or picture may be accommodated, and by tightly pressing the said hooks against the picture the latter will be held in immovable 65 relation to the glass. Through the eye 7 a suitable chain or other flexible support 8 is threaded and drawn sufficiently taut, and after insertion of the chain or other flexible device through the eyes the latter are bent to 70 closely embrace the portions of the chain passing therethrough, or in some instances, if desired, the said chain may be arranged to loosely pass through the eyes and retained in the position shown by Figs. 1 and 2 by 75 bending the eyes sufficiently to close the latter. To the upper portion of the chain or other flexible device 8 a hanger 9 is secured, comprising opposite chain or other flexible lengths 10, converging toward an upper suspending-ring 11, to which they are securely fastened. By the use of the chain or other flexible device 8 the supporting strain is distributed around the picture and is concentrated directly at the four corners, the 80 weight of the picture and glass, as well as the 85 weight of the picture and glass, as well as the corner-supports, which is concentrated on the bottom of the chain or other device 8, being equalized throughout the entire chain 8 and taken up by the hanger 9.

90 As an auxiliary, though not essential in all instances, a securing bar or strap 12 is employed and has its terminals bent around opposite side edge portions of the picture and glass or other transparent covering. This 95 bar or strap extends transversely over the back of the picture 2, at about the center thereof, and serves to prevent the said picture from buckling or warping.

The improved construction and arrangement of parts disclosed provides a neat and pleasing means for securing a picture to a transparent covering, as well as a convenient and durable means for supporting or hanging

a picture and dispenses with the usual forms of frames or picture inclosures. The cost of manufacture of the improved corner-support and fastening as set forth is reduced to a minimum and an economical means for attaching and holding a picture in connection with a transparent face-plate is provided. The design of the chain or other flexible device 8 and the hanger 9, as well as the corner-supports, may be varied at will and the proportions modified to adapt the device to different-sized pictures.

Having thus described the invention, what is claimed as new is—

15 1. The combination with a picture and a transparent covering therefor, of corner-supports having adjustable eyes projecting outwardly therefrom, a flexible supporting ele-

ment threaded through the said eyes and surrounding the picture and covering, and a hanger secured to said flexible device.

2. The combination with a picture and a transparent covering therefor, of corner-supports and fasteners comprising bodies with pairs of inturned hooks on adjacent edges and adjustable eyes intermediate the said hooks, a chain threaded through the said eyes and surrounding the picture and covering, and a hanger attached to the upper part of the said chain.

In testimony whereof I affix my signature in presence of two witnesses.

JOHN T. NELSON.
